ABSTRACT

Workpiece finishing apparatus including an abrasive charged trough in which workpieces are subjected to reciprocating movement along a desired path fixed by the shape of a traverse guide. The finishing trough is moveable vertically to position each workpiece in the abrasive. Mechanism is provided to automatically sequentially control the feeding, chucking, finishing and removal of workpieces.

FIG. 25

AUTOMATIC RECIPRO-FINISHING MACHINE

BACKGROUND OF THE INVENTION

According to a known recipro-finishing machine, power driven means provide movement of a finishing trough up and down and reciprocating movement of a workpiece or workpiece holder for the finishing purpose, but conveying the workpiece or workpiece holder to and from, and loading and unloading thereof to and from, is always done by human labor.

Therefore, operators must carefully attend to all steps of the operation.

With more extensive use of such recipro-finishing machine, diverse types and/or sizes of workpieces must be handled, and this leads to an increase in human labor, which limits the finishing efficiency.

In view of this, the present invention provides an automatic recipro-finishing machine including, in combination with means for conveying workpieces or workpiece holder (hereinafter referred to as "the workpiece" unless otherwise specified), means for chucking the same, means for finishing or polishing surfaces of workpieces, means for stopping the same at a given position upon completion of one finishing cycle, and means for removing the same, which are all combined with means for controlling operations or movements of all the means in a predetermined sequence.

According to the known machine, workpieces are subject to a horizontally reciprocating movement in the finishing trough, and are finished through their contact or rubbing with abrasive chips. However, the machine according to the invention is constructed such that a reciprocating arm is provided which slides along a traverse guide, and this traverse guide may be built in any desired shape. Thus, the reciprocating arm is caused to move following the path of the traverse guide. By this construction, it is possible to improve the finishing efficiency and obtain smoothly finished or polished surfaces of workpieces.

BRIEF SUMMARY OF THE INVENTION

According to the invention, workpieces which are charged into a finishing trough filled with abrasive chips are subject to horizontally reciprocating movement, and, wherever necessary, vertically reciprocating movement, so that the workpiece surfaces are evenly finished or polished. A control means is provided which can control all the operations including conveying workpiece or workpiece holder on a feed position to and from the finishing apparatus, chucking and moving the same up to the finishing apparatus, finishing or polishing the same and returning finished workpiece to the feed position.

In order to attain these objects, a finishing trough which is movable up and down is provided at the lower portion of a machine body which includes a number of vertical supporting members and a horizontal member supported thereby.

A hydraulic system is provided on both sides of the machine body for moving the trough up and down.

A table is provided at the lower front portion of the machine body. A rail mounting base is provided on both sides of the table, on which rails are placed and extend up to the side of the trough.

A horizontal or cross frame is provided below the horizontal member, and is equipped with a reciprocat-

ing arm slidable horizontally along a traverse guide. If the traverse guide is formed in any desired curve, the reciprocating arm can be moved along the curve. The reciprocating arm is provided with a clamp arm and a fluid means for operating the clamp arm.

The fluid means is operated by an instruction from a control system to cause the clamp arm to clamp or release the workpiece. In another embodiment of the invention, a means is provided for moving the workpiece up and down simultaneously with the horizontal movement thereof, so that the path of the workpiece can be adjusted.

BRIEF DESCRIPTION OF THE DRAWINGS

FIG. 1 is a front view of an automatic recipro-finishing machine embodying the invention.

FIG. 2 is a side view of the same.

FIG. 3 is a partially enlarged side view of an equipment for moving a carrier to and fro.

FIG. 4 is an enlarged view showing relative positions of limit switches for stopping movement of the finishing trough.

FIG. 5 is an enlarged front view of a device for stopping the workpiece in the middle of the reciprocating stroke thereof.

FIG. 6 is a side view of the same.

FIG. 7 is an outlined front view showing positions of limit switches which are mounted.

FIG. 8 is an outlined side view of the same.

FIG. 9 is a plan view showing an automobile bumper mounted on a workpiece holder.

FIG. 10 is a side view of the same.

FIG. 11 shows movement of the workpiece along a given path.

FIG. 12 is a sequence diagram for one embodiment of the invention.

FIGS. 13, 14 and 15 are circuit diagrams for the invention.

FIG. 16 is a fluid system diagram for the same.

FIG. 17 is a partially sectional front view of another embodiment of the invention wherein the workpiece is up and down simultaneously with reciprocation thereof.

FIG. 18 is a plan view of another equipment embodying the invention for loading and unloading the workpiece to and from the finishing apparatus.

FIG. 19 is a front view of the same.

FIG. 20 is a side view of the same.

FIG. 21 is a partially enlarged side view of a mechanism for driving a workpiece holder.

FIG. 22 is a partial side view showing the holder at a stop position.

FIG. 23 is a front view of an equipment for changing the proceeding directions of a carrier.

FIG. 24 is a plan view of the same.

FIG. 25 is a partially enlarged sectional view of the construction of a wheel for the carrier.

DETAILED DESCRIPTION OF THE INVENTION

The invention will further be described by way of examples only, with reference to the accompanying drawings. Referring to FIG. 1 and 2, the machine body comprises four vertical supporting members 1a, 1b, 1c and 1d and a horizontal member 2 supported thereby. A table 3 is provided at the front lower portion of supports 1a and 1b. A pair of bases 4a and 4b for mounting rails are provided on both sides of the table 3.

The rails 5a and 5b are laid on the bases 4a and 4b, respectively, horizontally and at right angle to the horizontal member 2. A workpiece carrier 6 is equipped with four wheels 7a, 7b, 7c and 7d, two wheels on opposite sides thereof and is movable on the rails 5a and 5b. As illustrated in FIG. 3, equipment for moving the carrier 6 is such that a fluid cylinder 8 is rigidly secured on the table 3, a piston rod 9 of the cylinder 8 being equipped with a flange 10 and the flange 10 having a pinion 11b rotatably connected thereto. The shaft 12 of the pinion 11b extends to connect to a pinion 11a of the same size as the pinion 11b. Engaging the pinions 11a and 11b, upper racks 13a and 13b are provided on the under side of the carrier 6 and lower racks 14a and 14b are provided on the upper side of the table 3.

As clear from FIG. 3, the carrier 6 can be moved relative to the table 3 by protruding the piston rod 9 of the cylinder 8. As the displacement of the carrier 6 is twice that of the piston rod 9, the carrier 6 can be moved a desired distance by moving the piston rod 9 half the desired distance. A pair of workpiece retainers 15a and 15b are provided above the carrier 6 and a workpiece 17 (for example, an automobile bumper is shown) loaded on a workpiece holder 16 is settled on the retainers 15a and 15b. Chutes 18a and 18b and buckets 19a and 19b are provided below the table 3 for receiving the abrasive chips which are attached to finished workpieces and dropped during the conveying operation.

As shown in FIG. 2, rails 20a and 20b are provided as extensions of the rails 5a and 5b, leading to the finishing apparatus, and the carrier 6 can be led into the apparatus along the rails 20a and 20b. A finishing trough 21 is provided below the rails 20a and 20b. The trough 21 has a smaller width than the distance between the two rails 20a and 20b. Brackets 22a and 22b are secured to the both sides of the trough 21.

The trough 21 is charged with abrasive media. Various sizes and shapes such as granular, globular triangular, cylindrical can be used as media. Abrasive media include, for example, gridding chips bound by inorganic or organic binders, sintered chips with fine-grained alumina and siliconia or organic grains such as chestnut shells and cone cores attached with fine-grained abrasives.

Choice of any of these abrasive media depends on the type and/or purpose of workpieces to be finished. On both sides of the horizontal member 2, there are provided frameworks 23a and 23 for fixing fluid cylinders 24a and 24b, the frameworks 23a and 23b extending upwards. The base ends of the cylinders 24a and 24b are connected at the top portion of the frameworks 23a and 23b and rotatable at slight angles. The tip end of piston rods 25a and 25b are connected to the brackets 22a and 22b and rotatable at slight angles. By introducing fluid pressure into the piston rod sides of the cylinders 24a and 24b, the trough 21 is moved up. When the carrier 6 is on the rails 20a and 20b at this moment, the carrier 6 is also moved up. The ends of a horizontal frame 26 are fixed on the top portions of the vertical supporting members 1a and 1b. Traverse guides 27a and 27b are fixed on the frame 26 longitudinally thereof. Guide rollers 29a, 29b, 29c and 29d of a reciprocating arm 28 are held and guided by the traverse guides 27a and 27b.

Movement of the reciprocating arm 28 follows after along the shape of the traverse guides 27a and 27b. A

cylinder 30 is connected on the arm 28, and clamp arms 32a, 32b, 32c and 32d in the form of a bell crank are provided on the lower opposite sides of the arm 28, and are rotatably fixed by pins. A clamp head 31 is connected to the piston rod 30a of the cylinder 30. The lower end of the clamp arms 32a, 32b, 32c and 32d are hook-shaped, and adapted to clamp the workpiece holder 16. Two vertical guides 33a and 33b are connected to the clamp head 31, and adapted to correct the direction of the moving clamp head 31. One of the guides 33a is equipped with a dog 34 which actuates limit switches LS 6 and LS 7.

In other words, when the piston rod 30a of the cylinder 30 is lowered, it turns the clamp portions of the arms 32a etc outwardly to release the holder 16. When the rod 30a is raised, it turns the clamp portions inwardly to clamp the holder 16.

Reinforcing members 35a and 35b are provided to connect the frame 26 to the member 2 thereby reinforcing the frame 26. One end of a driving rod 36 is rotatably connected to an end of the arm 28, and the other end of rod 36 is rotatably connected to a pin 37a of an eccentric plate 37. The eccentric plate 37 is rotated by a main motor 38 through pulleys 61 and 62 and a belt 63. A compound tank 39 is provided on the member 2 in order to feed compound into the trough 21.

Now, the operations will be described according to the mechanism described above. All operations except loading and unloading of the workpieces on the holder 6 at a feed position A are automatically carried out as shown in the sequence diagram of FIG. 12. As indicated in FIGS. 13, 14 and 15, these operations are automatically carried out by relays, timers and limit switches which are connected function of in the manner shown in the sequence diagram of FIG. 12. Positions of limit switches and other control devices are indicated in FIGS. 1 and 2, and diagrammatically in FIGS. 7 and 8. Before starting the operations, the carrier 6 with holder 16 carrying the workpieces 17 is located at a workpiece loading position A. This position can be checked by a limit switch LS1 which is contacted by a dog 40 of the pinion shaft 12. At this moment, the clamp head 31 is placed in a lower position with the arms 32a, 32b, 32c and 32d open. This position can be checked by a limit switch LS 6 located on the arm 28 and which is contacted by the dog 34 on the guide 33a fixed to the clamp head 31. The trough 21 is also located in a lower position. This position can be checked as indicated in FIG. 4, in which a bracket 22b, for example, is provided with a two-headed dog 44, and limit switches LS3, LS4 and LS5 are provided in a spaced relation on the wall 45. The lower position of the trough 21 can be checked by the limit switch LS3 which is pressed by a lower portion 44b of the dog 44. The limit switch LS4 is used to correct the position where the workpiece is chucked on the finishing apparatus and the limit switch LS5 is used to check the position where the trough 21 is up. This will be further described hereinafter.

These initial conditions will be satisfied when all operations end properly, but may not be so if the operations should be interrupted by power failure or other accidents. In such cases, it is desirable that a manual switch or switches be provided for returning the system to the initial conditions, or a circuit be added which enables a depressed preparatory switch to return the sys-

tem to the initial conditions. An interlocking circuit is preferably provided for the operative circuit so that the machine remains inoperative even when a start button is depressed, if the initial conditions should not be satisfied.

Shape of a workpiece holder depends on the type of workpiece to be finished. In other words, if a workpiece has a shape that can be held by chucking means, there is no need of the holder. However, workpieces such as automobile bumpers should desirably be mounted on the holder. In this case, a number of workpieces are carried by a holder as indicated in FIGS. 9 and 10 which can be held by the chucking means. The means by which workpieces are mounted and securely held on the holder may be lever means as indicated in FIGS. 9 and 10 or may be screwing means. This is not limitative in embodying the invention. A workpiece 17 is placed on the workpiece retainers 15a and 15b. When the start button is depressed, then the hydraulic cylinder 8 (referred to as SOL1 in FIG. 15) actuates the carrier 6 to move forward.

The movement of the carrier 6 is detected by a limit switch LS2, which causes the hydraulic cylinders 24a and 24b (referred to as SOL3) to actuate to lift the trough 21 as its relay circuit is thereby actuated. When the workpiece is not chucked on the chucking arms 32a, 32b, the upper dog 44a act on the limit switch LS4 to withdraw fluid pressure from the piston rod side of the cylinders 24a and 24b so that the movement of the trough 21 may be interrupted. At this moment, the workpiece 17 is between the clamp arms 32a, 32b, 32c and 32d. This position can be detected by the limit switch LS4 which is contacted by the lower dog 44b.

The sequence circuit works to introduce fluid pressure into the piston side of the cylinder 30 under the control of the circuit SOL3. The clamp head 31 is then raised to clamp the workpiece 17 with the clamp arms 32a, 32b, 32c and 32d. This clamping is detected by a limit switch LS7 which is contacted by the dog 34, and the circuit causes the trough 21 to move down. This movement is detected by the limit switch LS3 which advances the sequence by one step to withdraw the carrier 6. This withdrawal is detected by the limit switch LS1, which then starts the main motor 38 and moves the trough 21 up therewith. When the workpiece is clamped by the arms, or when the limit switch LS7 is working, the trough 21 moves up to the position where the upper dog 44a contacts the limit switch LS5. At this moment, the reciprocating member goes into the abrasive media of the trough 21. Then, the workpiece is moved in the abrasive media so that the surface thereof may be polished.

The reciprocating arm 28 is usually moved in a linear direction, but as indicated, the guide rollers 29a, 29b, 29c and 29d can also be moved along the path of the traverse guides 27a and 27b to move the workpiece along the path of the curved shape of the traverse guides 27a and 27b. This curved shape may be properly determined so as to obtain better finishing efficiency.

Reference numerals 17, 17a, 17b and 17c in FIG. 11 indicate positions of the workpiece which is moved to and fro along a curved path in the finishing operation with the trough 21 in an upper position. In FIG. 11, the workpiece takes the position 17d when it moves to the right of the figure, and it takes the positions from 17a, 17 to 17 when moving to the left.

Since the workpiece follows the upwardly curved path in the reciprocating motion, the contact of the surface to be polished and the media becomes very compact. According to the conventional machine in which the workpiece has a linear reciprocal motion, the front and rear bent portion e and side portion g of the automobile bumper in FIG. 11, for example, suffers wrinkles or tears due to the impact with the abrasive media. However, the present invention can diminish these disadvantages, and these portions can be polished as perfect as the portion f.

When the workpiece is finished with the upper surface thereof up as indicated by dot-dash-lines 17, 17a and 17c in FIG. 11, reciprocating in the arc-like path, the surface of the workpiece will receive a uniformly distributed weight of the abrasive media over the workpiece, and this minimizes the presence of voids which may momentarily arise between the workpiece and the media during the movement of the workpiece. This is an essential factor for obtaining a well-finished workpiece surface. When a workpiece has a different shape, it may easily be polished by moving it along a downwardly curved path. When a workpiece of a relatively longer length and an arc-like curved shape is to be finished, it may be placed with the inwardly curved surface up and moved along a downwardly curved path. In this invention, it is possible and easy to move the workpiece with the surface thereof to be finished down in a downwardly or upwardly curved path depending on the shape of the workpiece. This is of course within the technical scope of the invention.

Reference numeral 39 is a reservoir for compounds from which compound solution is fed into the trough 21. When a water gauge indicates its pipe 65 is full, as shown in FIG. 17, the workpiece is entirely in the compound solution. In this condition, the surface of the workpiece can be polished excellently. Chips of the media and filthy water that are produced in the trough 21 during polishing are discharged from a drain cock 64 provided at the bottom of the trough 21, and the bottom may be sloped for facilitating the drainage, as shown in FIG. 17. A discharge post may be provided in place of the drain cock 64 so that the filthy water may be filtered and returned by pumping means to the reservoir 39 for circulation. On completion of the finishing operation after a given period, the timer sends a signal to stop the main motor 38. At this moment, the reciprocating arm 28 must be located in the middle of its stroke, and therefore a device is provided on the disk plate 37 for adjusting the stop position of the arm 28 as indicated in FIGS. 5 and 6.

In other words, a switch plate 41 is provided on a supporting member 1d located near the disk plate 37, at the tip end of which a magnetic switch 42 is mounted. The disk plate 37 is equipped with an iron piece 43 having a protruded portion. When the iron piece 43 faces the magnetic switch 42, the magnetic action of the switch 42 sends a signal to the circuit and the main motor 38 is stopped. When the motor 38 is stopped, the trough 21 is moved down. This is checked by the limit switch LS3 and the carrier 6 is then moved forward.

This is checked by the limit switch LS2, and the trough 21 is then moved up. When the carrier 6 is in a forward position, the trough 21 is stopped midway by the limit switch LS4 which is located in the middle course of the trough 21. The cylinder 30 works to let the arm 32a, 32b, 32c and 32d release the finished

workpiece, and it is laid on the carrier 6. Then, the trough 21 is again moved down, and the hydraulic cylinder 8 is operated by an instruction from the limit switch LS3 to return the carrier 6 to its initial position. At this position, the finished workpiece is removed from the carrier by hand and a workpiece to be finished is loaded on the carrier. This workpiece will receive the treatment described above.

As described heretofore, the invention provides improvements over the prior art since it provides automatic loading and unloading of the workpiece to and from the finishing apparatus in addition to an automatic workpiece conveying means.

FIG. 16 indicates a hydraulic system for movement of the trough, operation of the clamp arms and conveying of the workpiece, in which reference numeral 114 is a motor, 115 is a hydraulic pump, V1, V2, V3, V4, V5, V6, V7 and V8 are check valves, and CV1, CV2, CV3, CV4 and CV5 are selector valves.

Referring now to FIG. 17, another embodiment of the invention will be described in which there is provided equipment for moving the workpiece in a curved path, with an up and down motion in addition to the horizontal movement thereof. Clamp arms 47 and 48 are connected by retainers 53 and 54 to piston rods 51 and 52 of hydraulic cylinders 49 and 50, said retainers 53 and 54 being equipped with guide rods 55 and 56 in parallel with the piston rods 51 and 52. The guide rods 55 and 56 are slidably passed through guides 57, 57a, 58 and 58a which are fixed to the fluid cylinders 49 and 50. The whole mechanism, including the fluid cylinders 49 and 50, is mounted on a branch arm 59 which is rigidly secured to a reciprocating shaft 60. The reciprocating shaft 60 is constructed such that it reciprocates by using a crank mechanism or the like via a linkage 61.

The fluid cylinder may be replaced by an electrically driven cylinder which can also serve the purpose of the invention. The workpiece 17 which is entirely in the abrasive media is moved to and from relative to the media by the reciprocating shaft 60. This is the same as with a conventional recipro-finishing machine. In this invention, however, a workpiece having curved or crooked surfaces can evenly be polished in the following manner.

When the workpiece is moved to the right as indicated by a solid line arrow 62 in FIG. 17, it should be in a position 17h. When moving to the left as indicated by an arrow 63, it should be in a position 17i. To this end, a limit switch LS9 is provided such that it contacts the end 59a of the branch arm 59 when the reciprocating shaft 60 is moved to the left extremity. When the limit switch LS9 is activated upon contact with the end 59a, the fluid cylinder 49 will have fluid pressure removed from the piston rod side thereof by the action of an electro-magnetic valve, while it will have fluid pressure transferred into the piston side thereof. At this moment, the fluid cylinder 50 will have fluid pressure removed from the piston side thereof while having fluid pressure into the piston rod side thereof. With the operations of these cylinders 49 and 50, the workpiece 17 which has been in the position 17i with the clamp arms in positions 47a and 48a will be moved to the right, taking the position 17h. By this movement, the crooked and plane portions of the right side of the workpiece (automobile bumper shown) can evenly be polished.

A limit switch LS10 is provided such that it contacts the end 59b of the arm 59 when the reciprocating shaft

60 is moved to the right extremity. The limit switch LS10 works upon contact with the end 59b to act on the electromagnetic valve to move the workpiece to the position 17i. While moving toward the left, the workpiece will have the left crooked and plane portions thereof polished. Compound solution is fed by the reservoir 39 into the trough 21 as previously mentioned, and is discharged from a cock 64 or can be circulated between the reservoir and the trough 21 by provision

5 of a rubber hose, a filter layer, and a pump. During the 10 finishing operation, it is desirable to keep the trough 21 to a given water level 66 by using an over flow pipe 65 so that the workpiece may always be immersed in the compound solution.

15 The embodiment described above is particularly suitable to a workpiece having crooked portions. Referring now to FIGS. 18 to 22, another embodiment of the invention will be described, in which a workpiece holder carrying a number of workpieces is provided and movable automatically in front of the finishing apparatus to and fro.

20 In FIG. 18, reference numeral 80 is a table on which a workpiece holder 81 is adapted to travel longitudinally by means of its wheels or guideway. Chains 84a and 84b and a drive motor 82 are provided for moving the holder 81. Reduction gears may also be provided for driving sprocket wheels 83a. The chain 84a, which engages with the sprocket wheels 83b can be moved to and from by normal or reverse rotation of the motor 25 82. As shown in FIGS. 18 and 21, chain 84a has drive pawls 85a, 85b, 85c, and 85d fixed thereto, which hold the holder therebetween and drive it. The finishing apparatus may be any of the types shown in FIGS. 1 and 30 17, or may be provided with a linear guide 88 as indicated in FIGS. 18 and 19.

35 Referring now to FIGS. 18 and 19, the recipro-finishing machine is supported by a frame 86. A traverse 87 is adapted to slide along a guide 88. The traverser 87 is driven by a reciprocating motor 89, a cam 40 wheel 90 and a crank arm 91. The holder 81 carrying the workpiece 17 is held by chucking heads 92a, 92b, 92c and 92d. The trough 21 is moved up by fluid cylinders 93a and 93b for the finishing operation as described. Fluid cylinders 94 and 95 are provided for 45 loading and unloading the holder 81 to and from the finishing apparatus.

50 Now, the operations of the embodiment just described will be described, as follows. All operations except those for attaching and detaching workpieces to and from the holder are automatically carried out. These operations are sequentially controlled, and are performed by the combination of relays, timers, and limit switches. At the start of operations, it is assumed that one holder 81a is now in a finishing process in the finishing apparatus while another holder 81b, in which finished workpieces have been replaced assumed workpieces to be finished, is waiting at the position 96c as indicated in FIG. 18. At the end of a given period of the finishing operations, a timer is actuated to stop the motor 89.

55 The positioning device as indicated in FIGS. 5 and 6 then causes the traverser 87 to stop at an unloading position. A relay is thus actuated to introduce fluid pressure into the piston side of the fluid cylinder 95, so that an unloading pawl 97 fixed to the piston rod of the cylinder 95 pushes the holder 81 forward to a position 60 96b. This movement of the holder 81 is detected by

LS11 which actuates to start the motor 82 to drive the chain 84. The pawls 85b and 85d, and 98a and 98b move the holders 81a and 81b to the right, respectively. When the limit switches LS12 and LS13 are contacted by these pawls, then the motor 82 is stopped.

At this moment, the holder 81 is stopped at a position 96a by ball stoppers 99a and 99b, each having a limit switch LS13 and LS14 below, as shown in FIGS. 18 and 22. An interlocking circuit is provided such that a next operation is only begun when both of the ball stoppers 99a and 99b or limit switches LS13 and LS14 are depressed by the holder 81. A circuit is added to the interlocking circuit, in which the motor is caused to rotate by small increments as the holder is moved slightly to the left when only the limit switch LS13 is actuated, and it is moved slightly to the right when only LS14 is actuated.

At this moment, the holder 81b is located in the position 96b while the holder 81a is in the stopper 96a. The holder 81b is loaded into the finishing apparatus as the fluid cylinder 94 works as indicated in FIG. 20. After the holder 81b has been loaded, the workpiece in the holder will receive the finishing process. The motor 82 is then caused to rotate reversely to drive the pawls 85a and 85c to move the holder 81a to the left. This movement of the holder 81a is detected by the limit switch LS15 which is depressed by the pawl 98a, for example, to stop the holder 81a at the position 96c. At this position, removal of the finished workpiece from and attachment of a workpiece to be finished to the holder are manually performed.

At this stage, the system is automatically restored to its initial position, and the operation is repeated as described before. According to the embodiment described above, as the holder carrying workpieces are provided movably in front of the finishing apparatus to and from, and yet automatically, no other operators are needed except one who is exclusively engaged in attaching and detaching workpieces to and from the holder. This remarkably contributes to reduced labor needs.

Now, another embodiment of the invention will be described with reference to FIGS. 23 and 24, which is concerned with equipment for moving a carrier and changing the direction thereof. A table 100 is provided on which a carrier 103 is moved longitudinally and is used for arranging workpieces on the carrier. Two rails 101a, and 101b are provided in parallel, which are each substantially as long as the table 100. The carrier 103 is moved along the rails 101a and 101b for the same processes as those described in conjunction with FIG. 18, up to rails 104a and 104b which are additionally provided at certain angles (at right angles, for example, shown in FIGS. 23 and 24) to the rails 101a and 101b. At the cross portions of these rails, there are provided cut outs 105a, 105b, 106a, 106b, 107a, 107b, 107c and 107d for the rails, respectively, to facilitate movement of a roller 105 as shown in FIG. 25.

The carrier 103 has four shafts 108a, 108b, 108c and 108d fixed at the four corners thereof. These shafts have horizontal wheels 109a, 109b, 109c and 109d rotatably mounted, said horizontal wheels being rotatable along the rails 101a, 101b, 104a and 104b and supported by a thrust bearing 110 provided between each of the wheels and the carrier 103. The shafts 108a, 108b, 108c and 108d have rollers 105a, 105b, 105c and 105d mounted rotatably along the walls of the rails

101a, 101b, 104a and 104b. Transportation of the carrier 103 on rails 101a and 101b can be either by rotating a pulley connected to the shaft 108a or 108c, said pulley being driven by a motor mounted on the carrier

5 103 or by the same mechanisms as those described with reference to FIGS. 18 to 22. The carrier 103 is stopped at a suitable position by the action of the limit switch as indicated in FIGS. 18 and 19, and at a definite position workpieces are arranged on the carrier 103.

10 When the carrier 103 is stopped at the position as indicated in FIG. 24, the rollers 105a, 105b, 105c and 105d are located opposite the cutout portions 106a and 106b of the rail 101a. At this position, the carrier 103 can be turned in a different direction (at a right angle as indicated) to move on the rails 104a and 104b. The rails 104a and 104b are extended beyond the table 100 to reach the inside of the finishing apparatus 102. The carrier can be moved along the rails 104a and 104b into the apparatus 102. The finishing apparatus may be any of the types shown in FIGS. 1, 17. The workpiece 17 is held by the chucking device out of the carrier 103 and the carrier 103 is returned onto the table 100. The workpiece 17 is then polished in the finishing apparatus.

25 In the meantime, the carrier 103 is moved in either direction, right or left, and stopped at a suitable position where workpieces to be finished are arranged and mounted on the carrier 103. Then, the operations will be repeated as described above. The carrier 103 is moved into the finishing apparatus by the forward movement of the piston rod 113a of a fluid cylinder 112. The carrier 103 is moved from the apparatus to the bed 100 by another fluid cylinder (not shown) 30 which is provided behind the apparatus.

35 I claim:

1. An automatic recipro-finishing machine, comprising:

traverse guides operatively mounted on said machine;

a trough adapted to be filled with abrasive media; means operatively coupled to said traverse guides for

finishing a workpiece by reciprocating said workpiece in said trough while filled with abrasive media, said means reciprocatively moving said workpiece along a path defined by the shape of said traverse guides;

means operatively mounted for conveying workpieces to and from said finishing means;

means operatively mounted for chucking said workpiece over said finishing means;

means operatively coupled to said finishing means for stopping said workpiece at a given position after the finishing operation has been completed; and

means operatively coupled to said finishing means, said conveying means, said chucking means, and said stopping means for controlling the operations thereof in a predetermined sequence.

2. An automatic recipro-finishing machine according to claim 1 wherein said reciprocating movement follows a straight path.

3. An automatic recipro-finishing machine according to claim 1 wherein said reciprocating movement follows a curved path.

4. The automatic recipro-finishing machine of claim 1 further comprising means operatively positioned for moving said workpiece at a side of and parallel to said

11

trough, said means being operatively coupled to said controlling means.

5. An automatic recipro-finishing machine according to claim 4 wherein said means for moving and means for conveying workpieces are comprised of two sets of rails on the horizontal plane and perpendicular to each

12

other, wheel means mounted on said rails, roller means rotatable along the side of said rails, and cutout portions provided at a turning point of said rails for facilitating movement of said roller means.
